(57) **CLAIM**

The ornamental design for a lid and upper regions of a container combination, as shown and described.

DESCRIPTION

FIG. 1 is an exploded isometric view of the lid and upper regions of a container combination of our invention;

FIG. 2 is a top plan view thereof;

FIG. 3 is a top plan view of the upper regions of the container with the lid removed;

FIG. 4 is an exploded front elevational view of the invention of FIG. 1, the left side elevational view being a mirror image thereof; and,

FIG. 5 is a rear elevational view thereof, with the lid removed, the right side elevational view being a mirror image thereof. The broken lines in the drawing depict environmental subject matter only and form no part of the claimed design.
